MATHIAS HAHN, OF AACHEN, GERMANY, ASSIGNOR TO HUBERT KRANTZ, OF AACHEN, GERMANY

FLAT-PRESSING OF TEXTILE FABRICS

Application filed October 12, 1929, Serial No. 399,335, and in Germany October 20, 1928.

This invention relates to the flat-pressing of textile fabrics using an apparatus comprising a press for hot pressing a portion of the fabric web, a further press for simultaneously cold pressing a corresponding previously hot pressed portion of the fabric web and means for conveying the fabric web through the presses.

In known apparatus of this kind the fabric is passed through the presses by pairs of co-operating rollers, which are arranged in front of, between and behind the presses, respectively. These rollers are either driven at a uniform speed or a certain acceleration in the direction of feed is imparted to certain rollers of the several sets. This arrangement has the following drawbacks: The fabric is constantly under a certain tension during the pressing, namely the tension exerted by the conveying rollers. However, in flat presses it is of the greatest importance to avoid any stretching of the fabric in order to obtain a product which does not crumple in use. Moreover, the position of the fabric fibres in the cold press becomes different from that in the hot press. This change of the position of the fibres is due to the fact that the fabric is drawn through the presses, but it is mainly due to the direct influence—contact and friction—of the feed rollers on the fabric. A proper pressing, which provides for a fixing of the hot pressed fibres by the subsequent cooling or cold pressing, is thus rendered impossible; on the contrary, the fibres will be fixed in a position different from that in which they have been hot pressed, so that the pressing effect is bad or even entirely useless.

One object of the present invention is to avoid the aforesaid drawbacks of the known continuous hot and cold presses. To this end, the fabric is placed on a travelling carrier on which it rests free from strains, and said travelling carrier constitutes the sole support for the fabric during its travel from the first to the last press of the pressing machine and traverses both the hot and the cold press thereof. Said carrier, which may for instance consist of an endless conveying band, is moved from the hot press into the cold press in

such a manner that no displacement of the fabric with respect to the carrier and no mutual displacement of the fabric fibres can take place. A stretching of the fabric and a change of position of the fibres or staple is thus avoided with certainty during the entire pressing process so that a pressing effect perfect in every respect and a uniformly good product are obtained.

Another object of the invention is to provide a simple and efficient mechanism for controlling the movements of the presses and fabric conveying means, such mechanism comprising an electric contact drum which is constantly rotated by the drive of the fabric conveying means and which is adapted to actuate a plurality of suitable electric operating devices designed to cut in and out the medium for operating the presses and the coupling for connecting the fabric conveying means with their drive.

In order more clearly to understand the invention reference is made to the accompanying drawings which illustrates, by way of example, a pressing apparatus arranged and constructed in accordance with the invention, and in which:

Fig. 1 is a side elevation, partly in section, of the pressing plant;

Fig. 2 shows the driving mechanisms for the fabric conveying means and presses and the control device for these mechanisms; and

Fig. 3 is a development of an electric contact drum forming part of the control device.

A and A¹ are the two presses which consist of the vertically movable press tables 1 and 2 and the top pieces 3 and 4, the two presses having pressing surfaces of equal breadth B. The pressing surfaces of the press A are formed by electrically or otherwise heated plates 5 and 6, while those of the press A¹ are formed by hollow plates 7 and 8 which are cooled by water or any other suitable medium. The movement of the press tables 1, 2 is effected by power cylinders 9 and 10. Both cylinders are connected by pipes 11 with a hydraulic double valve 12, Fig. 2, which regulates the supply and discharge of the pressure medium.

13 denotes the fabric to be treated which is passed through the presses by means of feed and guide rollers 14 and 15, one or both of which are positively driven. In the present 5 instance, it is assumed that only the roller 15 is positively driven. In order to pass the fabric through the presses in a condition free from strains so as to secure a uniform good finish, said fabric is carried by an endless belt 10 18 which runs over the rollers 14, 15 and further guide rollers 16, 17 and which traverses both the hot press and the cold press. The fabric after leaving the second press A¹ passes over a roller 20 driven by a chain 19 or 15 the like from the roller 15 to a plaiter 21.

The double valve 12 is controlled by a lifting magnet 22. The valve casing is connected by a conduit 23 with the delivery chamber of a pump 24 and with an accumulator 25. A return conduit 26 connects the valve casing with the fluid reservoir of the pump 24.

The roller 15 of the conveying device is driven by a belt pulley 27 which is mounted 25 loosely on an extension of the shaft of the roller 15, see Fig. 2. Mounted on the shaft extension is also a coupling sleeve 28 which is shiftable axially by means of a lever 29 actuated by a lifting magnet 30 and which is 30 adapted to couple the pulley 27 with the roller 15. The belt pulley 27 simultaneously drives through a gear 31 an electric contact drum 32 which has contacts 33 and 34. The contacts 33 and 34 cooperate with contact 35 fingers 35 and 36, respectively. The contact fingers 35 serve to close and open through a switch 37 the circuit for the lifting magnet 30, while the contact fingers 36 effect through a switch 38 the closing and opening of the 40 circuit for the lifting magnet 22.

The drawings show the press tables 1 and 2 in their lowered position. The lifting magnet 30 is energized due to the fact that the contact fingers 35 are in touch with one 45 of the contacts 33, and therefore the pulley 27 drives the conveying roller 15 through the coupling sleeve 28. The fabric is thereby advanced a distance corresponding to the breadth B of a press table. In the meantime 50 the contact drum 32 has rotated so much that the contact fingers 35 are disengaged from the contacts 33. The magnet 30 is de-energized and the feed of the fabric through the roller 15 is stopped instantaneously. During 55 the time the fabric moves forward the upper cone of the double valve 12 is closed because of the magnet 22 being de-energized, while the lower cone of the valve is open so that the pressure fluid can flow from the 60 power cylinders 9 and 10 through the pipes 11 and 26 into the reservoir of the pump 24. After the forward movement of the fabric has been stopped, the contact drum 32 has 65 brought one of its contacts 34 into engagement with the contact fingers 36. The mag-

net 22 is energized and the double valve 12 is actuated so that the lower cone controlling the return flow closes, while the upper cone controlling the supply of the pressure fluid opens. The pressure fluid accumulated in the accumulator 25 now flows through pipe 23, valve 12 and pipe 11 into the power cylinders 9 and 10, the accumulator 25 coming to a standstill when the full pressing pressure is attained. The fabric is instantaneously 70 pressed and brought to the desired temperature between the heated surfaces 5 and 6, while at the same time a previously hot-pressed portion of the fabric of the same dimensions is rapidly cooled under equal pressure between the cooled surfaces 7 and 8. When the hot-pressing and cold-pressing period has terminated, the two tables 1 and 2 move down into their lower position, the feed of the fabric is again initiated, and so 75 on, so that the pressing process is rendered continuous.

The pressing action can be changed within vast limits by changing the temperature of the heating and cooling surfaces and the 80 height of the pressing pressure which is dependent on the pressure of the accumulator. Besides, it is possible to vary within vast limits the duration of pressing by altering the length of the contacts 34 of the contact 85 drum 32. Instead of the lifting magnets there may also be used other electric devices for generating the required power, such as 90 motors or the like; the control valve 12 and the coupling 28 may also be actuated by mechanical means such as cams, grooved cylinders, or the like.

Having thus described my invention, what I claim as new and desire to secure by Letters 95 Patent is:

1. A method of flat-pressing fabrics consisting in intermittently conveying the fabric forwardly ahead in a substantially even plane through separate hot and cold presses and during the conveying and pressing supporting the fabric so as to prevent stretching of the fabric and mutual displacement of the fabric fibres.

2. An apparatus for flat-pressing fabrics comprising successively arranged hot and cold presses with their pressing surfaces on substantially the same level, a traveling carrier for supporting and conveying the fabric and arranged to traverse both the hot and cold presses in a straight line, and means for alternately moving the carrier forwardly ahead and actuating the presses.

3. An apparatus for flat-pressing fabrics comprising hot and cold presses arranged one in succession of the other and with their pressing surfaces on substantially the same level, an endless conveying band for supporting the fabric and carrying it through the presses in a straight line, driving and guide rollers for the conveying band ar-

ranged to guide the band with its fabric supporting stretch forwardly ahead through both presses, and means for alternately moving the conveying band and actuating the presses.

- 5 4. An apparatus for flat-pressing fabrics, comprising hot and cold presses, endless conveying means for carrying the fabric through the presses, actuating means for the presses, 10 a drive for the conveying means, and an electric contact drum constantly rotated by the said drive and adapted to control the movements of the endless fabric conveying means and of the presses.
- 15 5. An apparatus for flat-pressing fabrics, comprising hot and cold presses, an endless conveying band for supporting and carrying the fabric through the presses, power cylinders for operating the presses, valves for admitting pressure fluid to and discharging it from the power cylinders, means for actuating these valves, guide and feed rollers for the fabric conveying band, a drive for at least one of the feed rollers, a clutch for connecting the drive and disconnecting it from such feed roller, means for actuating this clutch, and an electric contact drum constantly rotated by the said feed roller drive and adapted to control both the movements of the 20 25 30 said valve actuating means and of the clutch actuating means.
6. An apparatus for flat-pressing fabrics, comprising successively arranged hot and cold presses, an endless conveying band for supporting and carrying the fabric through the presses, power cylinders for operating the presses, valves for admitting pressure fluid to and discharging it from the power cylinders, a lifting magnet for actuating these valves, an electric circuit for this lifting magnet, guide and feed rollers for the fabric conveying band, a drive for at least one of the feed rollers, a clutch for connecting this drive with and disconnecting it from 35 40 45 such feed roller, a lifting magnet for actuating this clutch, an electric circuit for this clutch actuating magnet, and an electric contact drum operatively connected with the said drive for being constantly rotated by the same and adapted to control the circuits for the said lifting magnets.

In testimony whereof I have signed my name to this specification.

MATHIAS HAHN.
